UNITED STATES PATENT OFFICE.

JOSEPH B. PERRY, OF PROVIDENCE, RHODE ISLAND, ASSIGNOR OF ONE-HALF TO
HARRY FOWLER, OF PROVIDENCE, RHODE ISLAND.

ASSORTING MACHINE.

Application filed July 17, 1925. Serial No. 44,253.

To all whom it may concern:

Be it known that I, JOSEPH B. PERRY, a citizen of the United States, residing at Providence, in the county of Providence and 5 State of Rhode Island, have invented certain new and useful Improvements in Assorting Machines, of which the following is a specification.

My invention relates to a machine for 10 sorting screw blanks, screws, pins, needles, bolts, and other objects.

An object of my invention is to separate from sweepings and scrap in assorted sizes the screws, blanks, or other articles finished 15 or unfinished therein contained, whereby a saving of material and labor is effected.

Another object is to automatically gage the articles during the sorting operating, and insure micrometric accuracy and similarity in the successively segregated masses. 20

Further objects are stability, simplicity, and facility of operation.

To the above ends primarily my invention consists in such parts and in such combinations of parts as fall within the scope 25 of the appended claims.

In the accompanying drawings which form a part of this specification—

Figures 1, 2, and 3 are a plan view, a side 30 elevation, and an end elevation respectively of a machine embodying my invention, showing parts broken away,

Figures 4 and 5, sections of the same on lines 4—4 and 5—5 respectively of Figure 1, 35 Figure 6, a fragmentary plan view of the table with the gage casing and wooden top plate removed, and

Figures 7 and 8, sections on line 7—7 of Figure 1, and line 8—8 of Figure 6 respectively. 40

Like reference characters indicate like parts throughout the views.

In the form of my invention herein shown a framework 11 comprises a rectangular or 45 oblong frame 12 carried by corner legs 13 connected by end bars 15, which in turn are connected by longitudinal spaced bars 16, carrying transverse parallel guide bars 17 for an open box 18 adapted to slide on the 50 bars 16. A cast iron bed frame 20 rests on the frame 12 and is attached thereto in this instance by screws 21 in depending perforated lugs 22 thereon. The frame 20 comprises a flat body 23 provided with a central 55 oblong opening 24, and lateral longitudi-

nally disposed guides 25 integral with the top face of the body, provided upon their adjacent faces with longitudinally disposed stepped lower and upper grooves or seats 26 and 27 respectively. A funnel 36 of thin 60 sheet metal below the open frame 20 is fixed at its upper edge by screws 37 to the four sides of the frame 12. The retracted open end 38 of the funnel terminates above the 65 slidable box 18. Upon one end of the plate 20 centrally thereof is a depending lug or ear 40, as shown in Figure 5 provided with a central opening 42 to receive a rotatable shaft or screw 43 having annular retaining shoulders 45 at each side of the lug and provided with a thread 46. Fixed to the outer end of the shaft is an operating wheel 48. The thread 46 engages the thread 49 of an opening 50 in a depending ear or lug 51 centrally located near one end of a rectangular 70 metallic frame 53 slidable in the guideway formed by the grooves 26. This frame has a central oblong opening 54 adapted to register with the opening 24 of the frame body 23. Transversely of the opening 54 are flat 75 bars 56 integral therewith or attached thereto by screws 57 in their ends. These bars are laterally spaced from each other, the spaces being indicated by 58.

Covering the frame 53 and its cross bars 80 is a metallic plate 61 resting on the guides 25 and attached to the latter at its corners in this case by screws 62. This plate has transverse slots or openings 64 forming resultant integral cross bars 65. A portion 66 of the 85 plate 61 at one of its ends is not slotted in this instance. Fixed to or integral with the lower faces of the several cross bars 65 are narrower bars 68 disposed lengthwise of the latter with their ends projecting beyond the 90 bars 65 and resting in the grooves 27. In this case the bars 68 are attached at their centers to the bars 65 by screws 70, and at their ends, to the guides 25 by screws 71. One corresponding lateral edge of each bar 100 68 slightly projects laterally from the edge of its bar 65 forming a resultant shoulder 73.

As herein shown the plate 61 has a marginal beveled abutment. This consists of an 105 oblong frame 75 resting upon the plate whose central opening 76 exposes the cross bars 65 and the unslotted portion 66. The frame 75 has depending lateral fingers 77 glued or otherwise fixed thereto extending 110

between pairs of lateral lugs 78 on the sides of the guides 25 and attached by screws 79 at their lower ends to the frame 12.

Cooperating with the above described assorting means and operated thereby is an indicating or gaging means which in its preferred form of embodiment includes, as shown in Figure 1 and in Figures 6 to 8 inclusive, a metal strip 81 attached by screws 82 to the margin of plate 61 upon whose end is soldered a housing 83 in which slides a rack 84 provided with a hole 86 to receive a pin 88 fixed in one of the bars 56 and passing through an oblong slot 89 in the plate 61. The rack engages and rotates a pinion 90 upon a vertical driving pin 91 journaled in openings 92 in the housing. The upper portion of the pin or shaft 91 is flat and registers in an axial slot 93 in the lower end of a shaft 94 passing through a hole 95 in the side 96 of a cylindrical housing or casing 97 provided with a back 98 and a dial plate 99. The shaft 94 is journaled in holes 100 in a bracket 101 fixed by rivets 102 to the casing back 98. A gear 103 on the shaft 94 engages a gear 105 on a spindle 106 journaled in holes 107 and 108 in the casing back and dial respectively. Upon the projecting end of the spindle is a pointer 110 adapted to cooperate with micrometric graduations 112 upon the dial face. The casing is supported by an arm 114 fixed at its upper end by the rivets 102 to the casing back 97; and at its lower outwardly flanged end 115 by rivets 116 to a base plate 117 fastened by screws 118 to the plate 75. The plates 75 and 117 are respectively cut away at this point to form cavities 120 and 121 accommodating the adjacent operating parts.

In operation the rotation of the shaft 43 by turning the operating wheel 48 in either direction increases or diminishes the spaces between the adjacent sides or edges of the movable cross bars 56 and the stationary bars 65 with their depending laterally extending shoulders 68.

The movement of the frame 53 carrying the bars 56 is communicated by the latter to the gage pointer through pin 88, rack 84, pinion 90, split shaft 91, 94, gears 103, 105, and spindle 106. The outward movement of the frame 53, increasing the inter bar spaces, advances the pointer 110 which measures micrometrically upon the graduations 112 of the dial plate the width of the bar spaces.

The articles to be sorted, say screw blanks, are dumped upon the plate 61 within the beveled abutment 75, and by a brush, or otherwise the mixture is spread until the articles of small size depend between the cross bars which have been spaced by the operating wheel 48 a predetermined dis-

tance. This spacing is facilitated, in the case of articles of slightly varying sizes, by the cooperating gage mechanism. In the drawings is shown a screw 122 with the bar 56 and the side of the shoulder 68 engaging the shank of the screw, while the head of the screw rests upon the top of the bar and shoulder. The remaining articles of the mixture of larger sizes are next brushed to the right upon the unslotted portion 66 of the plate 61. Thereupon the plate 53 is advanced to increase the extent of the spaces and permit the heads of the screws to pass therethrough and fall into the receptacle 18. The operator slides the box from its seat, empties it, and replaces it for its next load. The mass of articles upon the unslotted area are now brushed over the slotted portion of the plate, and the above described operation repeated as often as required by the number of varying sizes. Obviously when the articles to be sorted are headless they initially pass between the adjusted bars instead of being first suspended therebetween.

I claim:

1. In an assorting machine, an open bed frame, a frame slidably supported on the bed frame, cross bars on the slidable frame, a stationary plate supported by the bed frame, cross bars on the stationary plate, shoulders on the second cross bars projecting intermediate the first cross bars, and an operating screw connecting the two frames.
2. In an assorting machine, an open bed frame, a frame slidably mounted upon the bed frame, cross bars on the slidable frame, a stationary plate supported by the bed frame above the slidable frame, cross bars on the stationary plate, depending shoulders on the second cross bars extending between the first cross bars, and an operating screw connecting the two frames.
3. In an assorting machine, an open bed frame, lateral guides upon the bed frame, a frame slidably mounted on the bed frame between the guides, cross bars on the slidable frame, a stationary plate fixed to the guides above the slidable frame, cross bars on the stationary plate, depending laterally projecting shoulders upon the second cross bars in the plane of the first cross bars, and an operating screw connecting the frames.
4. In an assorting machine, an open bed frame, lateral guides upon the bed frame, a frame slidably mounted on the bed frame between the guides, cross bars on the slidable frame, a stationary plate fixed to the guides above the slidable frame, cross bars on the stationary plate, depending shoulders on the second cross bars between the first cross bars, a marginal abutment upon the stationary plate, and an operating screw connecting the frames.
5. In an assorting machine, a framework,

an open bed frame supported by the framework, a funnel mounted on the framework below the bed frame, a lug on the bed frame, a frame slidably mounted upon the bed frame, a lug on the slidable frame, cross bars on the slidable frame, a stationary plate supported by the bed frame above the slidable frame, cross bars on the stationary plate, depending shoulders on the second cross bars 5 projecting between the first cross bars, and an operating screw journaled in the lugs.

6. In an assorting machine, an open bed frame, a frame slidably supported by the bed frame, interspaced cross bars on the 15 slidable frame, a stationary plate supported by the bed frame, cross bars on the stationary plate, shoulders on the second cross bars in the spaces between the first cross bars, an operating screw connecting the frames, 20 a device for gaging the spaces between the

first cross bars and the shoulders, and means actuated by the screw for operating the gaging device.

7. In an assorting machine, an open bed frame, a frame slidably supported by the bed frame, interspaced cross bars on the slidable frame, a pin carried by the slidable frame, a stationary plate supported by the bed frame above the slidable frame provided with a slot to receive the pin, cross 25 bars on the plate, a casing supported by the bed frame above the plate, a dial in the casing, a spindle rotatably mounted in the dial, a pointer on the spindle, an operating screw connecting the plates, and means actuated 30 by the pin for actuating the spindle.

In testimony whereof I have affixed my signature.

JOSEPH B. PERRY.
